VENTILATED FABRIC, GARMENT, AND
METHOD OF MAKING THE SAMEAlfred A. Glidden, Watertown, Mass., assignor to
Hood Rubber Company, Inc., Watertown, Mass.,
a corporation of Delaware

Application September 27, 1938, Serial No. 231,894

7 Claims. (Cl. 154—2)

This invention relates to ventilated or breathable fabrics and to garments employing the same and methods of manufacture.

Heavy coats used in very cold climates permit and encourage the formation of perspiration, the dampness of which is dangerous to health and disagreeable. Similar difficulties are encountered with impervious rubberized fabric coats adapted for wear in warmer climates especially where the humidity is high.

The chief objects of this invention are to provide warmth and resistance to showers while at the same time providing ample ventilation, and to provide breathability uniformly distributed throughout a garment, and to provide a sheet material having these properties which readily may be made up into garments. A further object is to provide a weather-resisting fabric and garment that is breathable throughout very nearly its entire extent and with substantial uniformity throughout such extent.

These and other objects will appear from the following description and the accompanying drawings:

Of the drawings:

Fig. 1 is a front quarter view in perspective of one form of garment embodying the invention as in use.

Fig. 2 is a detail plan view of the material thereof, parts being broken away to show the construction.

Fig. 3 is a sectional view of the compound fabric employed, taken on line 3—3 of Fig. 2.

Fig. 4 is a rear view of the garment in use.

Fig. 5 is a front view of a modified form of garment in use.

Referring to the drawings, and first to Figs. 2 and 3, the material comprises a perforate backing or lining 10 to which are secured in overlapping or shingled relation a plurality and preferably a multiplicity of strips 11 of substantially impervious fabric of any desired construction. The strips are attached to the lining by one edge in any desired manner but preferably by a band 12 of adhesive applied to the under side of their upper margins. The strips may also be attached at intervals at positions below their upper margins so as to resist being turned up in the wind. The strips may be of heavy heat insulating cloth or of lighter cloth provided on its under face with a layer 13 of waterproof material such as rubber composition or other waterproof plastic, or the cloth may be otherwise treated to make it waterproof. The lining 10 may be of any breathable material such as pervious cloth.

An effective method of preparing the material is by printing the lining with a gridiron design of adhesive coating material, preferably having stripes of adhesive material 14 applied lengthwise 5 of the fabric and cross stripes 15 of similar material. While the deposited cementing material is still adhesive in nature the strips 11 of rubberized cloth or other material, preferably having an adhesive coating 12 of cementing material at 10 one edge margin thereof may be fed from supply rolls into engagement with the face of the lining so that their upper margins are adhered to the lining and the strips are pressed in place in overlapping or shingled relation.

15 Referring to Figs. 1 and 4, these illustrate a garment having a rear panel 16, a right front panel 17, and a left front panel 18, a collar 19 and raglan sleeves 20, 21. The front and rear panels are arranged so that the shingled strips 11 extend circumferentially of the body, and the sleeves are so arranged that the strips 11 extend circumferentially of the arm, the sleeves and body panels being united by stitched or other suitable seams. The collar 19 and belt 22 are made of 20 similar material but need not be of shingled construction. The patch pockets 23 however are made of shingled fabric corresponding with the coat, the upper margin of the pockets extending under, and being normally concealed by one of 25 the shingling strips of the body panel as at 24.

The garment of Fig. 5 is tailored of different style and is made up of shingle cloth material having shingle strips of greater width than that used in the garment of Figs. 1 and 4, the wider 30 strips giving the body and skirt portion a cape and flounce effect. This style is very suitable for raincoats made of rubberized fabric.

By varying the number and size of the shingles, the percentage of breathable area of the fabric 35 may be varied over a wide range, and while the protection against rain is complete, the breathable area may be made as high as 90 percent and greater of the area of the fabric, if desired, and distributed with substantial uniformity.

40 Variations may be made without departing from the scope of the invention as it is defined by the following claims.

I claim:

1. The method of making ventilated flexible material which comprises providing a pervious lining, disposing adhesive material in spaced apart zones upon said lining, and then adhering margins of covering elements to said lining at said zones in overlapping shingled relation of said elements to 50 provide ventilation between the shingled elements

and through the material, said adhesive material being disposed to adhere the covering elements at spaced-apart positions throughout a substantial part of the width of the strip to retain the strips in place against undesirable lifting thereof while providing such ventilation.

2. Ventilated flexible sheet material comprising a pervious flexible backing having spaced areas of adhesive material on one face thereof with intervening uncoated zones of the pervious backing and a plurality of strips of flexible weather-resisting material adhered to at least some of said areas of adhesive material on the backing and arranged in overlapping relation, providing for ventilation between the adjacent strips, said strips being adhered to said backing at one margin of the strip and also at spaced-apart positions throughout a substantial part of the width of the strip to retain the strip in place against undesirable lifting thereof while providing such ventilation.

3. Ventilated flexible sheet material comprising a pervious flexible backing having closely spaced narrow bands of adhesive material on one face thereof with intervening uncoated zones of the pervious backing, and a plurality of strips of flexible weather resisting material adhered to said narrow bands of adhesive material on the backing along a margin of each strip and arranged in overlapping relation, providing for ventilation between the adjacent strips, and said strips being adhered also at spaced-apart positions throughout a substantial part of the width of the strip to retain the strips in place against undesirable lifting thereof while providing such ventilation.

4. Ventilated flexible sheet material comprising a pervious flexible backing, and on one face thereof of a coating of adhesive material disposed in a gridiron pattern providing crossed narrow bands of the adhesive material and interposed uncoated areas of the previous material, and a plurality of strips of weather-resisting material upon the backing in overlapping relation, said strips having adhesive material on the under faces thereof united with the adhesive material of the gridiron pattern on the backing along a margin of each strip providing for ventilation between the adjacent strips, and said strips being adhered by such gridiron pattern also at spaced-apart positions throughout a substantial part of the width of the strip to retain the strip in place against undesirable lifting thereof while providing such ventilation.

5. The method of making ventilated flexible material which comprises providing a pervious backing of flexible material, applying adhesive material in closely spaced zones upon one face of the backing, and then adhering a plurality of strips of weather-resisting material to said zones of the adhesive material on the backing along one margin of each strip with the strips in overlapping relation to permit ventilation therebetween, and also adhering said strips at spaced-apart positions throughout a substantial part of the width of said strips to retain the strips in place against undesirable lifting thereof while providing such ventilation.

15 6. The method of making ventilated flexible material which comprises providing a pervious backing of flexible material, applying adhesive material in closely spaced narrow bands upon one face of the backing, and then adhering a plurality of strips of weather-resisting material to said bands of adhesive material on the backing along one margin of each strip with the strips in overlapping relation to permit ventilation therebetween, and also adhering said strips at spaced-apart positions throughout a substantial part of the width of said strips to retain the strips in place against undesirable lifting thereof while providing such ventilation.

20 7. The method of making ventilated flexible material which comprises providing a pervious backing of flexible material, applying adhesive material upon one face of the backing in a gridiron pattern of crossed narrow bands of the adhesive upon the backing, providing a plurality of strips of weather-resisting material with adhesive material upon the face of each strip, applying said strips to said backing in spaced-apart overlapping relation with adjacent strips, pressing the strips upon the backing to unite the adhesive material of the strips with the adhesive material on the backing in an arrangement to permit ventilation through the backing between adjacent strips, said crossed narrow bands of adhesive being so disposed as to adhere said strips at a margin thereof and also at spaced-apart positions throughout a substantial part of the width of the strip to retain the strips in place against undesirable lifting thereof while providing such ventilation.

50

ALFRED A. GLIDDEN.
